US0D1101500S

(12) **United States Design Patent** (10) Patent No.: **US D1,101,500 S**
(45) Date of Patent: ** Nov. 11, 2025

(54) **CRUET**

- (71) Applicant: **TURKIYE SISE VE CAM FABRIKALARI ANONIM SIRKETI**, Istanbul (TR)
- (72) Inventor: **Bahadir Haktanir**, Istanbul (TR)
- (73) Assignee: **TURKIYE SISE VE CAM FABRIKALARI ANONIM SIRKETI**, Istanbul (TR)

(**) Term: **15 Years**

(21) Appl. No.: **35/521,790**

(22) Filed: **May 20, 2024**

(80) **Hague Agreement Data**

Int. Filing Date: **May 20, 2024**
Int. Reg. No.: **DM/238546**
Int. Reg. Date: **May 20, 2024**
Int. Reg. Pub. Date: **Jul. 26, 2024**

(30) **Foreign Application Priority Data**

- Nov. 20, 2023 (TR) 2023/011696
- (51) **LOC (15) Cl.** **07-06**
- (52) **U.S. Cl.**
